UNITED STATES PATENT OFFICE.

CHARLES J. TRINKAUS, OF CHICAGO, ILLINOIS.

HYDRAULIC JACK FOR STUMP-PULLERS.

1,102,825.

Specification of Letters Patent.

Patented July 7, 1914.

Application filed May 10, 1912. Serial No. 696,412.

To all whom it may concern:

Be it known that I, CHARLES J. TRINKAUS, a citizen of the United States, residing at Chicago, in the county of Cook and State 5 of Illinois, have invented certain new and useful Improvements in Hydraulic Jacks for Stump-Pullers, of which the following is a specification, reference being had therein to the accompanying drawing.

10 This invention relates to stump pullers of that type in which the operating power is manual.

The invention has for its principal object to improve and simplify the construction 15 and operation of manually operated stump pullers so as to be thoroughly reliable, efficient and successful in use, and so designed that a man alone can operate the machine to extract large trunks from the earth.

20 Another object of the invention is the provision of a hydraulic jack or motor so arranged and combined with winding drums that a powerful draft can be produced on the cable or cables that are adapted to wind 25 on the drums to extract the stumps, there being a ratchet and pawl device between the jack and drums whereby the latter can be turned step by step by the reciprocation of the piston of the hydraulic jack or motor.

30 In carrying out the invention, the winding drums are mounted on the body of a vehicle and two cables lead from the drum to the stumps to be pulled, one cable having its ends so arranged as to wind under the 35 drums, while the other cable winds over the top of the drums, both cables exerting the same draft on the stumps so that that stump having the weakest hold will be loosened first. If both stumps pull simultaneously,

40 the vehicle remains stationary, whereas the vehicle moves toward the immovable or firmer stump, as the weaker stump is being extracted. The drums are connected together on a single shaft which has fastened 45 thereto a ratchet wheel located between the drums, and mounted to swing on the shaft is a lever which carries a pawl that engages the ratchet wheel so as to turn the latter step by step as the lever is oscillated. This 50 lever which hangs from the drum shaft has its lower end connected with a piston rod of a motor or hydraulic jack that is mounted on the vehicle in such position that as the piston reciprocates, the drums will be turned. Hydraulic pressure is applied to 55 the piston of the motor by means of a pump

which is mounted at the side of the vehicle body and operated by the attendant, the pump being equipped with a reservoir that contains oil, alcohol, water or any other hydraulic medium, which is used over and over again in the operation of the motor. By operating the pump, the motor is moved on the power stroke to turn the drums, and on the reverse stroke, the hydraulic medium 60 is forced out of the motor and back to the reservoir of the pump. In other words, the pump and motor form what is ordinarily termed a hydraulic jack. The return stroke of the motor is effected by means of a lever which is fulcrumed on the vehicle body at one side and extends therefrom to the opposite side so as to be conveniently within reach of the attendant while operating the pump. The attendant first operates the 65 pump lever until the motor has completed its power stroke and then the valve-controlling device of the pump is manipulated so that the return lever can now be operated to force the hydraulic medium back to the 70 reservoir. By repeating these operations, the cables are wound on the drums as the 75 stumps are pulled.

For a more complete understanding of the details of the invention, its objects and 80 advantages, reference is to be had to the accompanying drawings, which illustrate one embodiment of the invention, and in which,

Figure 1 is a plan view of the machine. Fig. 2 is a side view of the machine. Fig. 3 is a front view of the stump pulling machine. Fig. 4 is a detail view of the pawl and ratchet operating means for the drums.

Similar reference characters are employed to designate corresponding parts throughout the views.

Referring to the drawings, A designates the body of the vehicle on which the stump pulling apparatus is mounted, the said body, 90 while it may be of any approved construction, being in the present instance, of rectangular form and made of side I-beams 1 and front and rear cross beams 2 and 3. The body rests on I-beam sills 4 that are disposed 95 and suitably connected with the front and rear axles 5 and 6, respectively, and on the axles are traction wheels 7. For conveniently moving the device from place to place, a tongue 8 with suitable draft means 100 is applied for hitching horses to the machine.

The stump pulling mechanism comprises, in the present instance, two drums B which are located in axial alinement and fastened to a common shaft 10 which extends transversely of the body A and journaled in bearings 11 which are secured to brackets 12 fastened to side beams 1 of the body A, so that the drums are supported in an elevated position. The drums are spaced apart and 5 the drum shaft has fastened thereto a large ratchet wheel 13 which is spaced from the adjacent ends or heads of the drums. Hanging from the shaft is a lever 14 made in two sections which have their upper ends pivoted on the drum shaft so as to freely swing back and forth thereon as a center, and between the lower ends of the sections of the lever is carried a pawl 15 fulcrumed at 16 and having the extremity 17 heavier than 10 the nose of the pawl, so that such nose will be maintained in contact with the ratchet teeth of the wheel 13. This lever is adapted to have a back and forth swing of about sixty degrees, more or less, the forward 15 swing causing the drums to turn in an anti-clockwise direction, Fig. 2, for winding the cables, while the rearward swing is the idle stroke and brings the pawl into position to impart another partial turn to the drums on 20 the next forward stroke. Coacting with the ratchet wheel is another pawl 18 which is fulcrumed at 19 on a cross beam 20 firmly secured to the vehicle body and having its ends strengthened by braces 21. This pawl 25 18 is constantly in engagement with the ratchet teeth and maintains the draft on the cables during the return stroke of the operating lever.

The turning of the drums through the 40 ratchet and pawl mechanism is accomplished by a hydraulic motor or jack C which is located centrally of and at the rear of the vehicle body A, the said motor comprising a cylinder 22 which is horizontally disposed and contains a piston or plunger 23 that has its front end connected by a hinge joint 24 with the rear end of a connecting rod 25, which rod has its forward end hingedly connected at 26 with the lower 45 end of the pawl-carrying lever 14. The cylinder of the motor is secured to and set in between the rear cross beam 3 and another cross beam 26 which extends transversely of the vehicle body and is secured to the side beams thereof. 50

The motive medium is supplied to the motor or jack through a pipe 27 which connects with the rear end of the cylinder so that the medium acting on the rear end of 55 the piston or plunger 22 will force the same forwardly and cause the pawl-carrying lever to swing in the same direction and turn the drums. This pipe 27 connects with a pump device D secured by bolts 28 to the right side beam of the body A. This pump

device D is substantially the same as the kind used in connection with hydraulic jacks and includes a pump 29 that draws its supply from a reservoir 30 and delivers the hydraulic medium through the pipe 27, 70 there being the usual pressure gage 31 connected with the delivery side of the pump. After the motor piston has been moved to the end of its power stroke, the hydraulic medium is forced back to the reservoir by 75 manipulating the valve-controlling means 32, such means being commonly employed in hydraulic jack outfits. The pump is operated by a lever 33 which is fulcrumed at 34 and is linked to the plunger of the pump 80 29. By moving the operating lever 33 up and down, the water or other hydraulic medium is supplied to the motor. The lever 33 is of considerable length so that great power can be exerted by a single man. The return of the motor piston is accomplished by another lever 35, which, as shown in Fig. 1 is fulcrumed at 36 to one side of the vehicle body and extends therefrom to the pump side, where the free or handle end 37 can 85 be conveniently within reach of the operator while standing at the pump lever. This piston returning lever 35 extends under the connecting rod 25 and is suitably connected therewith, as for instance, by a pin 38 on 90 the rod 25 extending into a slot 39 in the lever. The lever 35 is in the full line position, Fig. 1, at the beginning of the power stroke and when it reaches the dotted line position 40, the operator stops operating the 95 pump lever 33 and manipulates the valve controlling device 32, and then moves the handle end of the lever 35 rearwardly to its full line position, thereby forcing the hydraulic medium out of the cylinder 22 100 through the pipe 27 and back to the reservoir 30 where such medium can be used over again during the next stroke.

Two cables E and F are used in connection with the drums B. The forward cable 110 E has its ends secured by pins 41 to the inner heads of the drums and are adapted to wind on the drums from the top. The rear cable F is fastened by pins 42 to the outer heads of the drums and is adapted to wind around the latter from underneath. At the rear of the vehicle body A is a horizontal roller 43 that is disposed under the rear cable F so as to support the latter out of contact with the vehicle body and provide for the easy winding of the cable. 115

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment 125 130

ment thereof, I desire to have it understood that the apparatus shown is merely illustrative, and that such changes may be made when desired as are within the scope of the 5 claims appended hereto.

Having thus described the invention, what I claim as new, is:—

1. The combination of a four-wheel truck, a hydraulic cylinder jack mounted thereon, 10 mechanism mounted on said truck to be driven by said jack, a piston rod, a connecting rod pivotally attached to the piston rod and connecting said rod with said mechanism, a pump for applying pressure to said 15 jack to move the piston in one direction, and a horizontal piston return lever fulcrumed on said truck to move in a horizontal plane extending across and having a jointed connection with said connecting rod, said pump embodying a hand lever operable at the 20 same side of the truck as said piston return lever.

2. The combination of a four-wheel truck,

a hydraulic cylinder and piston jack mounted on said truck, a piston rod, a connecting rod jointed to the piston rod, mechanism on said truck driven by said connecting rod, a hand operated piston return lever fulcrumed on one side of the truck extending transversely of the latter and projecting 25 from the opposite side thereof, a jointed connection between said lever and rod whereby the piston is moved on its return stroke by said hand lever, and a pump mounted on said truck connected with the 30 jack for supplying fluid under pressure thereto to effect the forward stroke of the piston, said pump having an operating lever disposed at the same side of the truck as the free end of the piston return lever. 40

In testimony whereof I affix my signature in presence of two witnesses.

CHARLES J. TRINKAUS.
